ATTORNEY.

UNITED STATES PATENT OFFICE

GEORGE F. WIKLE, OF MILWAUKEE, WISCONSIN, ASSIGNOR TO THE FISK RUBBER COMPANY, OF CHICOPEE FALLS, MASSACHUSETTS, A CORPORATION OF MASSACHUSETTS

TIRE BUILDING MACHINE

Application filed April 27, 1927. Serial No. 186,960.

My invention relates to machines for building pneumatic tire casings on substantially flat drums or formers and more particularly to a device for stitching down the carcass 5 plies and elements, such as the tread rubber, side walls, chafing strips etc.

Among the objects of my invention is the provision of a device of this character in which the stitching rolls are completely within 10 the control of the operator. Other and further objects will be apparent from the following specification and claims:

In the accompanying drawings which illustrate one embodiment of my invention,

15 Figure 1 is a side elevation of a building machine equipped with my device and showing the latter in operative position,

Figure 2 is a similar view showing the device in inoperative position.

20 Figure 3 is a front elevation of the structure as shown in Figure 1,

Figure 4 is a detail view, partly in section showing the mounting of the stitcher and its drive,

25 Figure 5 is a section on line 5—5 of Figure 3, and

Figure 6 is a section on line 6—6 of Figure 4.

Referring to the drawings 1 designates the 30 collapsible building drum which is secured by means of any suitable type of collapsing chuck 2 to a shaft 3 adapted to be rotated as desired by a motor or other source of power positioned within the machine housing 4.

35 The stitching device comprises end frames 6 and 7 held in spaced relation by hollow shafts 8 and 9, shaft 8 supporting stitching rolls 10 and 11 as hereafter described. End frames 6 and 7 are pivoted at their upper ends on a shaft 12 adjustably secured at one end in a slotted bracket 13 secured to the housing 4 at 14. The device as a whole is adjustably positioned on shaft 12 by collars 15 and 16.

40 Stitching discs 10 and 11 are simultaneously moved toward and from each other on shaft 8 by means of a reversely threaded shaft 18 rotatably mounted in shaft 8. The stitcher discs are provided with shoulders 19 internally grooved at 20 to receive an arcuate 45 block 21 secured as by screw 22 to a traveler

23, which passes through slots 17 formed in hollow shaft 8 and rides in the threads 24 of shaft 18. Shoulders 19 are apertured at 25 to permit access to screw 22. As will be evident discs 10 and 11 are freely rotatable on 55 hollow shaft 8 but rotation of shaft 18, through travelers 23 and blocks 21 riding in grooves 20, moves the discs transversely toward and from each other along shaft 8.

Shaft 18 is rotated by means of gear segment 27, secured to one end of a shaft 28 passing through hollow shaft 9, meshing with a gear 29 secured to one end of the shaft 18. Gear segment 27 is operated by a handle 30 secured to the opposite end of shaft 28.

55 The stitcher discs are swung into operative position against the tire carcass 31 on drum 1, as shown in Figures 1 and 2, by means of a handle 32 secured to side frame 7.

60 As will be evident, the initial setting of discs 10 and 11 and their speed of separation are completely controlled by the operator through handle 30 while the degree of pressure applied is controlled by the pressure applied to handle 32.

65 In stitching down the carcass plies and tread, the drum being set in rotation in the direction of the arrows in Figures 1 and 2, the stitching discs are set in central position and swung against the drum by means of 70 handle 32. Handle 30 is then operated to gradually separate the discs and stitch down the carcass plies or tread from their center to their edges. If desired the discs may be initially set at the edges of the carcass and 75 moved inwardly to stitch down turned back portions of the carcass plies, or they may be applied in intermediate positions to stitch down chafing strips and the like.

I claim:

1. A device of the character described comprising a frame pivoted adjacent a tire building drum, a slotted hollow shaft forming part of said frame, stitcher rolls rotatably mounted on the hollow shaft, a reversely threaded shaft rotatably mounted in the hollow shaft, blocks riding in the threads of said threaded shaft and operatively connected, through the slots in the hollow shaft, to the stitcher rolls, a handle adapted to 95 100

rotate the threaded shaft to simultaneously move the stitcher rolls toward and from each other and a second handle secured to the frame, to swing the latter about its pivot to 5 press the stitcher rolls against a tire carcass on the drum.

2. Stitching mechanism for a tire building machine comprising a hollow shaft provided with a longitudinal slot, a stitching roll 10 mounted for free rotation on said shaft and provided on its bearing surface with an annular groove, a spirally grooved shaft rotatably mounted in the hollow shaft, a block riding freely in the groove of the spirally 15 grooved shaft and extending through the longitudinal slot of the hollow shaft into the annular groove on the bearing face of the stitching disc, and means to rotate the spirally grooved shaft.
- 20 3. Stitching mechanism for a tire building machine comprising a pair of stitching rolls mounted on a common shaft for free rotation in parallel planes, and means to simultaneously move said rolls toward and from each 25 other along said shaft to position them in selected spaced stitching relation prior to the stitching operation.

In testimony whereof I have signed my name to the above specification.
